Frank R. Outerbridge and Raymond Harvey,
New York, N. Y., assignors to The Pantasote
Leather Company, Passaic, N. J., a corporation of New Jersey

Application June 22, 1934, Serial No. 52,388

Term of patent 14 years

To all whom it may concern:

Be it known that we, FRANK R. OUTERBRIDGE, a citizen of the United States, residing in the Borough of Manhattan, city, county and State of New York, and RAYMOND HARVEY, a subject of the King of Great Britain, residing in the Borough of Manhattan, city, county and State of New York, have invented a new, original, and ornamental Design for a Textile Fabric or Similar Article of Manufacture, of which the following is a specification, reference being had to the accompanying drawing, forming a part thereof, and showing a face view of a piece of textile fabric embodying our design.

The design is intended to be repeated on the textile fabric as shown.

We claim:

The ornamental design for a textile fabric or similar article of manufacture substantially as shown and described.

FRANK R. OUTERBRIDGE.
RAYMOND HARVEY.
